UNITED STATES PATENT OFFICE.

DECAIRE CEEL, OF CAUGHNAWAGA, QUEBEC, CANADA.

LACROSSE-STICK.

No. 891,813.

Specification of Letters Patent.

Patented June 30, 1908.

Application filed July 5, 1907. Serial No. 382,179.

To all whom it may concern:

Be it known that I, DECAIRE CEEL, of Caughnawaga, in the county of Laprairie, in the Province of Quebec, Canada, have invented certain new and useful Improvements in Lacrosse-Sticks, of which the following is a specification.

My invention relates to improvements in lacrosse sticks, and the objects of my invention are: firstly, to improve the construction of the wooden frame by strengthening it and lightening it at certain points; secondly, to improve the construction of the wooden frame so as to maintain the guard in such position that it will not be materially displaced; thirdly, to lock the upright supports for the guard members to the top-guard member in such a manner as to maintain the said guard-members always in proper position; fourthly, to so lace the guard as to prevent the guard from material displacement, and fifthly, to improve the construction of the wooden-frame so as to form a positive pocket in the head of the lacrosse stick so that the ball may be positively caught therein.

The construction of my lacrosse stick will be hereinafter fully set forth.

Figures 1 and 2 are perspective views of my lacrosse stick. Fig. 3, is a front side elevation of same. Fig. 4, is a detail view of portion of the wooden frame. Figs. 5 and 6 are rear and front perspective views of two uprights for supporting the guard-members. Figs. 7, 8 and 9 are respectively cross-sections on the lines *a—b*, *c—d*, and *e—f*, Fig. 1. Fig. 10, is a perspective view of my lacrosse stick showing an alternative form of means for tightening the members of the guard. Fig. 11, is a view of a portion of a lacrosse stick showing my improved construction of frame for forming a positive-pocket in the lower portion of the head of the lacrosse stick, and Fig. 12 is an enlarged perspective view of an improved method of lacing the cross members of the netting to the longitudinal members.

In the drawings like characters of reference indicate corresponding parts in each figure.

It is well known that in connection with lacrosse sticks, players often find that the guard-members are not thoroughly reliable and thus are apt to be displaced and not hold the ball securely in place; now I construct the lacrosse stick so that it may be light and

strong and yet at the same time maintain the guard-members in such position that they cannot be materially displaced.

The top edge *A* of the back *B* of the lacrosse stick is extended beyond the point as shown at *C* where the upper guard-member *D* rests upon said top edge *A*, and far enough so as to prevent said upper guard-member *D*, from displacement sufficient to destroy the efficiency of the guard *E* which is composed of said upper guard-member together with the lower guard-member *F* and the intermediate guard-member *G*. Of course the upper guard-member *D* is passed through any suitable hole *H* formed in the handle *I* and in such position that when the upper guard-member *D* is passed therethrough and made taut, it will always rest upon the top edge *A* of the back *B* in the position shown in Figs. 1, 2, and 3. The intermediate guard-member *G* is passed through a hole *3* made in the lacrosse stick some distance from the hole *H* so that the said intermediate guard-member will occupy a position extending outward beyond the guard-members *D* and *F*, thereby giving the guard the inward-set position shown particularly in Figs. 1 and 11, thus making the guard-members *D* and *G* overhang the netting forming the lacrosse-head. In place of using the hole *3*, I may attach the intermediate guard-member *G* to the lacrosse stick by means of any suitable loop *4* which passes through a loop *5* formed in the end of the guard-member *G*: this construction just described is a very convenient one for tightening the guard-members when they become loose.

The toe *J* of the lacrosse stick is shaped substantially as shown in the drawings, and upon referring to Fig. 3 particularly, it will be seen that said toe extends above the netting, thus placing its corner *j* in such position in relation to the point *C* on the top edge *A* of the back *B* (that is to say, the point or position on said top edge *A* against which the upper guard-member *D* rests) that the upper guard-member *D* (which passes through the hole *K* in said toe) will be held by said toe so that the upper guard-member *D* will always be maintained in such position that it cannot ordinarily be moved thereout, and thus maintain the proper position of the guard *E*. The upper guard-member *D* is preferably passed over the

corner *j* of the toe *J*. Upon referring to Fig. 4 it will be seen that the bend of the toe *J* (when the back *B* is in the position shown in this figure) will be preferably within the 5 portion *L* of said toe which is really the point where it extends from the bend or elbow *M* of the lip *N* which in turn extends from the back *B* through the bend or elbow *O* of said back. Therefore, it will be understood that 10 the toe *J* besides extending above the netting also preferably extends towards the back *B*. I am aware that lacrosse sticks now made are provided with these toes, but same are not given the same shape and position as mine so that it will coöperate with a 15 certain point on the top edge *A* of the back *B* so as to maintain the guard *E* in such position that it cannot be materially displaced. Lacrosse players find it very 20 exasperating when they cannot depend upon the permanency of the guard. Now by means of the construction shown and described in the drawings, it will be understood that the guard-member *D* will be positively supported 25 at both ends by the frame of the lacrosse stick in addition to the fact that it is anchored thereto by the holes *K* and *H*. Supporting the upper guard-member *D* as described will insure the other members *F* 30 and *G* being held in proper position.

In order to prevent the lacrosse stick from breaking where the back *B* extends from the handle *I*, I make it stout or thick at the portion *a* and so place the hole *H* therein that it 35 will not materially weaken the stick at this point. For the same purpose I increase the thickness of the wood at the bends or elbows *M* and *O* as shown at *b*¹ and *c*¹ (Figs. 7 and 9) forming the lip *N* between these bends or 40 elbows shallower as shown at *d*¹ (Fig. 8), thus so distributing the weight and thickness of the wood as to strengthen the stick at the points required and lighten it at other points. When the guard *E* is tightened up it will be 45 understood that the lip *N* will more or less bend, causing increased force to act upon the bends or elbows *M* and *O*, and by so strengthening same as before described and not unduly weakening the lip *N* by reducing 50 the thickness of wood as before described, I prevent the breaking of the lacrosse stick at these particular points under ordinary usage. By giving the toe *J* the pronounced bend as before described, I prevent same from being 55 appreciably moved out of these positions when the guard *E* is tightened up.

The netting passed through the different holes *i* is made of the ordinary gut or thongs, woven or held in relation to each other after 60 any suitable manner. I may use any suitable intermediate guard-supports in connection with the guard *E*, but I prefer to use the guard-supports I am about to describe, as I find that the peculiar way in which they are 65 locked to the upper guard-member *D* of the

guard *E* prevents them from being laterally displaced. The intermediate guard-supports *l* are constructed preferably of one strand *n* of gut or any other suitable material which is twisted around itself as shown 70 in the drawings, and as is usual in connection with lacrosse manufacture, so that the intermediate guard-member *G* and lower guard-member *F* may be supported thereby, as shown at 2 and 3¹ (Fig. 5). The strand *n* is 75 further coiled or looped around the longitudinal member *m* of the netting which is laced to the lacrosse stick after any suitable manner. This strand *n* is also passed around the upper guard-member *D* so as to provide 80 two loops *p* and *q* and a third loop *r* which passes between the twisted parts of said strand *n* after the manner shown at *s* in Fig. 6, so that when the strand *n* is drawn tightly 85 in position the loop *r* will force the loops *p* and *q* tightly around the upper guard-member *D* and thus effectually lock the intermediate guard-supports *l* from lateral displacement. In Fig. 12 I show a form that I 90 may use, if desired, in lacing the cross-members of the netting to the longitudinal-members. In place of merely twisting the cross-members around the longitudinal-members, I may twist the cross-members around each other as shown at 4¹ and then loop them 95 around the longitudinal-members 5: This construction shortens the cross-members of the netting preventing them from being unduly shifted longitudinally of the longitudinal members 5, thereby preventing unduly large 100 holes being formed in the netting through which the ball would be likely to pass.

Upon referring to Fig. 11 it will be seen that the back *B* is provided with a sharp bend *6* which is a short distance beyond the 105 handle *I*: by constructing this bend in the back *B* and constructing the guard *E* so as to obtain the proper set of same, I provide a positive pocket in the lower portion of the head of the lacrosse stick whereby the ball 110 can be always caught by the player.

By one skilled in this art it will of course be understood that various changes may be made in the construction of my lacrosse-stick as shown and described, which yet will not 115 depart from the spirit of my invention.

What I claim as my invention is:

1. A device of the class described, consisting of a wooden frame integrally formed and comprising a handle; a back; the lip, 120 and the toe which is bent towards the back and above the upper surface of the lip; a netting laced in proper position, and a suitable guard laced in with said netting and laced through said toe and secured to said 125 back in such position that the upper guard-member thereof will always rest upon the top edge of said back so as to positively be supported thereby at this end which, together with the support given said upper 130

guard-member by said toe, effectually prevents the said guard from material displacement.

2. A device of the class described, consisting of a wooden frame integrally formed, and comprising a handle; a back; the lip, and the toe which is bent towards the back and above the upper surface of the lip; a netting laced in proper position, and a guard comprising the upper guard-member; the intermediate guard-member and the lower guard-member; intermediate guard-supports, comprising a strand of suitable material laced in with said netting and twisted around itself so as to give support to the intermediate and lower guard-members which are suitably laced through said toe and secured to said back near where the handle extends therefrom, and provided with two loops which fit around the upper guard-member, and a third loop which passes between the twisted parts of said strand and underneath said upper guard-member so that when the said strand is pulled into proper position during course of manufacture, the said loops will firmly grip around said upper guard-member and prevent said intermediate guard-supports from lateral displacement; the said upper guard-member being laced through said toe and secured to said back in such position that it will always rest upon the top edge of said back so as to be positively supported thereby at this end which, together with the support given said support given said upper guard-member by said toe, effectually prevents the said guard from material displacement.

3. A device of the class described, consisting of a wooden frame integrally formed comprising a handle; a back; the lip, and the toe which is bent towards the back and above the upper surface of the lip; the said lip being constructed thicker so as to give additional strength, at the points where the said toe extends therefrom and where it extends from said back, and being made thinner intermediate said points; the said wooden frame being made stouter or thicker at the point where said back extends from said handle; a netting laced in proper position, and a guard comprising the upper guard-member; the intermediate guard-member and the lower guard-member; intermediate guard-supports, comprising a strand of suitable material laced in with said netting and twisted around itself so as to give support to the intermediate and lower guard-members which are suitably laced through said toe and secured to said back near where the handle extends therefrom, and provided with two loops which fit around the upper guard-member, and a third loop which passes between the twisted parts of said strand and underneath said upper guard-member so that when the said strand is pulled into

proper position during course of manufacture, the said loops will firmly grip around said upper guard-member and prevent said intermediate guard-supports from lateral displacement; the said upper guard-member being laced through said toe and through said back in such position that it will always rest upon the top edge of said back so as to be positively supported thereby at this end which, together with the support given said upper guard-member by said toe, effectually prevents the said guard from material displacement.

4. The combination with a lacrosse-stick frame; a netting laced therein, and a guard; of intermediate guard-supports comprising a strand of material laced in with said netting and twisted around itself so as to give support to certain members of said guard, and provided with two loops which fit around the upper guard-member, and a third loop which passes between the twisted parts of said strand and underneath said upper guard-member so that when the said strand is pulled into proper position during course of manufacture, the said loops will firmly grip around said upper guard-member and prevent said intermediate guard-supports from lateral displacement.

5. A lacrosse stick frame comprising a handle made stout or thick at a point from which extends the back B; the lip N., elbows O. and M., and the terminal J, the stick being thickened at the elbows, and the elbow O. being thicker than the elbow M.

6. A device of the class described, consisting of a wooden frame integrally formed and comprising a handle, a back; and a lip, and a toe which is bent towards the back and above the upper surface of the lip; a netting laced in proper position, a guard laced in with said netting and comprising a top, a lower, and an intermediate member; the top-member being laced through said toe and secured to said back in such a position that it will always rest upon the top edge of said back so as to be positively supported thereby at this end which, together with support given said upper member by said toe, effectually prevents the material displacement of same, the said intermediate member being secured to said wooden frame at a point away from the point of attachment thereto for the upper guard-member, so as to give the proper set to the whole guard, and suitable supports for the said members.

7. A device of the class described, consisting of a wooden frame integrally formed and comprising a handle; a back extending therefrom and provided with a pronounced bend a short distance from where it extends from the said handle; the lip, and the toe; a netting laced in proper position, a guard laced in with said netting and comprising a top, a lower, and an intermediate member; the top member being laced through said toe and se-

14
cured to said back in such a position that it will always rest upon the top edge of said back so as to be positively supported thereby at this end which, together with support given said upper member by said toe, effectually prevents the material displacement of same, the said intermediate member being secured to said wooden frame at a point away from the point of attachment thereto for the 10 upper guard-member, so as to give the proper

set to the whole guard, and suitable supports for the said members.

In testimony whereof I have signed my name to this specification, in the presence of two subscribing witnesses.

DECAIRE CEEL.
